T. G. MARTIN.
AUTOMATIC TELEPHONE SYSTEM.
APPLICATION FILED DEC. 15, 1916.

Patented Apr. 27, 1920.

UNITED STATES PATENT OFFICE.

TALBOT G. MARTIN, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

1,338,318.

Specification of Letters Patent. Patented Apr. 27, 1920.

Application filed December 15, 1916. Serial No. 137,153.

To all whom it may concern:

Be it known that I, TALBOT G. MARTIN, a citizen of the United States of America, and a resident of Chicago, county of Cook, 5 and State of Illinois, have invented certain new and useful Improvements in Automatic Telephone Systems, of which the following is a specification.

My invention relates in general to automatic telephone systems, and more particularly to automatic systems of the so-called two wire type in which the subscribers' lines are provided with individual line switches. In systems of the above general character, 10 upon the removal of the receiver at a calling substation the line circuit is closed to operate the individual line switch associated therewith at the exchange, whereby connection is extended to the first of the numerical 15 trunking switches to be used in establishing the connection. These numerical switches are responsive to momentary interruptions of the line circuit subsequently produced by the operation of a calling device with which 20 the substation is provided.

In the commercial operation of such systems it happens quite frequently that a calling subscriber, in removing his receiver to initiate a call, will accidentally manipulate 25 his switch hook so as to send a preliminary impulse over the line circuit immediately after the line switch has operated and before he has operated his calling device. In other words, if the receiver is carelessly re- 30 moved, the first closure of the line circuit may be followed by one or more interruptions before the receiver is completely disengaged from the hook. When this occurs, 35 it follows as a matter of course, that when the calling subscriber operates his calling 40 device the first numerical switch will already have been operated and that a wrong number will therefore be obtained.

The object of my invention is to obviate 45 the difficulty explained above by providing means for delaying the operation of the individual line switches. While the invention is applicable to various types of line switches including those of the rotary type, 50 it is especially well suited for use with the well known master switch controlled plunger type of line switches, and such embodiment will be described hereinafter, refer-

ence being had to the accompanying drawing. The figure of the drawing shows my 55 invention diagrammatically.

In the drawing, the reference character A indicates a calling automatic substation whose line conductors 11 and 12 have been extended through the medium of the individual line switch C to the trunk line terminating in the selector E. The line switch C, together with a number of similar line switches, is controlled in its trunk selecting operations by the master switch D. Inasmuch as all the apparatus shown is in general well known in the art, it will be described but briefly, reference being had to prior patents hereinafter mentioned in lieu 60 of a detailed description.

The substation A may be of any approved automatic type, such for example, as the substation shown in the British patent to Martin, No. 1419 of 1910. As represented herein, it comprises essentially the receiver 75 2, transmitter 3, switch hook 4, ringer 5, and condenser 6. Being an automatic substation, there is also provided a pair of impulse springs 7 and 8 controlled by an impulse wheel 9 through the medium of a finger hole dial (not shown).

The line conductors 11 and 12 of the substation A extend to the exchange where they terminate in the individual line switch C, which is of the general type of line switch 85 disclosed in the British patent to James, No. 26,301 of 1906; being, however, of the particular type shown in U. S. Letters Patent No. 1,078,690, reissued April 13, 1915, as No. 13,901, to Frank Newforth. Through 90 the medium of line switch C the line of substation A when calling is given access to a plurality of trunk lines each terminating in a numerical selector switch.

As previously mentioned, the line switch 95 C and a plurality of other line switches are controlled in their trunk selecting operations by means of a master switch D. The master switch D is of the general type of master switch disclosed in the above mentioned British patent to James, No. 26,301 of 1906; being, however, more nearly of the particular type disclosed in U. S. Letters Patent No. 1,185,510, granted May 30, 1916, to A. E. Keith. As is well known, the function of the master switch is to maintain the 100 105

plungers of all the idle line switches which it controls in position before the terminals of an idle trunk line.

One of the trunk lines to which the line switch C has access is indicated in the drawing by the reference characters 110, 120, and 130, and extends to the selector switch E, of which only the line and release relays are shown. The selector E may be of the type shown in the above mentioned patent to Newforth, No. 1,078,690.

While I have shown throughout the drawing a plurality of batteries, it is to be understood that there is preferably but one battery having its positive pole grounded, the various battery leads of the drawing being connected together and extended to the negative pole thereof.

Having given a general description of the apparatus involved, I will now proceed to explain more in detail the operation of the same. In the following, the operation of the line switch C in extending connection responsive to the removal of the receiver at substation A will be described, together with the consequent operation of the master switch D, particular mention being made of the new feature introduced by my invention.

When the calling subscriber at substation A removes his receiver to initiate a call, an energizing circuit is completed over the line conductors 11 and 12 for the line relay 14 of the line switch C, in the usual and well known manner. Upon attracting its armature, the line relay 14 closes a circuit for the pull in winding 18 which may be traced over the following path: ground at G', armature 20 and its working contact, pull-in winding 18, common conductor 21, windings 23 and 24 of relay 22 in series, and contact springs 26 to battery B. The winding 23 of relay 22 is of low resistance preferably not over 1 ohm, while the winding 24 should have at least 2500 ohms resistance. Consequently, upon the closure of the above circuit the pull-in winding 18 is not operatively energized. The relay 22, however, is energized over the above circuit, although this operation is delayed somewhat by reason of a slug of copper with which its core is provided, and upon attracting its armature 25, short-circuits its high resistance winding 24, thereby permitting sufficient current to flow to operatively energize the pull-in winding 18. Upon energizing, the pull-in winding operates both the plunger arm 15 and the cut-off armature 16; the former through the medium of its plunger (not shown) forcing the bank springs 30-33, inclusive, into engagement, respectively, with contacts 34-37, inclusive; and the latter disconnecting the line conductors 11 and 12, respectively, from ground and the line relay 14.

By the engagement of bank springs 30

and 33 with contacts 34 and 37, respectively, the line conductors 11 and 12 are placed in connection, respectively, with the trunk conductors 110 and 120, which terminate in the line relay 60 of the selector E. The line relay 60 is accordingly energized over the loop circuit including substation A and, upon attracting its armature, closes a circuit for the slow-acting release relay 61. Upon energizing in its turn, the release relay closes a holding circuit for the line switch C which may be traced as follows: ground at G², working contact of armature 63 and the said armature, conductor 130, contact 35, bank spring 31, and the holding winding 17 to battery B'. Since the line relay 14 is slow-acting, it retains its armature to maintain the pull-in winding 18 energized until after the above holding circuit has been established. A branch of the holding circuit extends by way of conductor 100 to multiple test contacts in the banks of connector switches having access to the line of substation A where by a ground potential on these test contacts the said line is made busy.

In the foregoing, it has been assumed, of course, that immediately prior to the removal of the receiver the plunger of the line switch C and other idle plungers of the group were standing in front of the terminal of the particular trunk line which is shown in the drawing and which extends to the selector E. This being the case, the master switch wiper 40 would at that time have been in engagement with the contact 41, the locking arm 42 would have been resting in notch 43 of the locking plate 46, and the arm 44 would have been in the proper position to close the contact springs 45. With the master switch in this position, as a result of the engagement of bank spring 32 with contact 36, a circuit for the starting relay 50 is completed by way of the master switch wiper 40. Upon energizing, the starting relay 50 completes a circuit which includes the low resistance winding of the supervisory relay 53 and the windings of relays 51 and 52 in parallel. The locking relay 51, upon attracting its armature, disconnects the battery from relay 22 in order to prevent the operation of any other line switches of the group while the master switch is moving their plungers to a new position, and at the same time disengages the locking arm 42 from the notch 43. The relay 52, upon energizing, completes a holding circuit to maintain the starting relay 50 energized after the wiper 40 has moved from contact 41, and also completes a circuit for the solenoid 55. The solenoid 55 now draws in its plunger, thereby rotating the plunger shaft 47 in clockwise direction until the locking plate 46 and the wiper 40 reach the position shown in the drawing. Although the circuit of relay 52 is at once 130

broken as soon as the arm 44 begins to move, its springs are retained in operated position by the detent 57 until the apparatus reaches the position shown, at which time 5 the detent is disengaged by the arm 58 and the springs are allowed to separate. The solenoid and the starting relay then de-energize, followed by the deenergization of the relay 51; the latter operation permitting 10 the locking of the shaft 47 through the engagement of the locking arm 42 with the last notch in the locking plate 46. It is understood that by the rotation of the shaft 47 as described, the plungers of all the idle line 15 switches of the group are moved into position before the terminals of the last or tenth trunk line, provided that such trunk line is not already busy. Subsequent calls will now operate the master switch under control 20 of relays 50 and 51 to permit backward rotation of the plunger shaft 47 by the spring 59, whereby idle trunks may be successively selected in the usual and well known manner.

25 The foregoing operations have all taken place in response to the removal of the receiver at substation A. The calling subscriber may now proceed to operate his calling device in accordance with the digits of 30 the desired number, whereby the selector E and succeeding switches are actuated in the regular manner to complete the required connection. Since this latter operation is well understood and is in no way concerned 35 with my invention the details thereof will be omitted.

40 It will be seen that my invention provides suitable means for delaying the energization of the operating magnets of the individual line switches in a telephone system of the general character described, whereby accidental interruptions of the line circuit incident to the removal of the receivers at calling substations are prevented from having 45 any ill effects on the successful operation of the system.

While I have shown and described in the foregoing a certain particular embodiment 50 of the invention, it is not to be limited to the precise form shown, but I desire on the contrary to include and have protected by Letters Patent all forms and modifications thereof which may come within the scope of the appended claims.

55 What I claim as my invention is:

1. In a telephone system, subscribers' lines, trunk lines, an automatic switch for interconnecting a plurality of said lines, means for initiating the operation of said 60 switch, and means common to said subscribers' lines for delaying the completion of the connection.

2. In a telephone system, subscribers' lines, trunk lines, an automatic switch for 65 interconnecting a plurality of said lines,

means responsive to the removal of the receiver on one of said lines for initiating the operation of said switch, and means common to said subscribers' lines for delaying the final connecting operation thereof. 70

3. In a telephone system, subscribers' lines, trunk lines, an automatic switch for interconnecting said lines, subscriber controlled means for initiating the operation of said switch, and automatic means common to 75 said subscribers' lines for delaying the completion of the connection.

4. In a telephone system, a subscriber's line, a trunk line, an automatic switch for interconnecting said lines, an operating magnet for said switch, a circuit for said magnet, and a device in said circuit for preventing the immediate energization of said magnet when the circuit is closed. 80

5. In a telephone system, a subscriber's line, a trunk line, an automatic switch for interconnecting said lines, an operating magnet for said switch, a circuit for said magnet, subscriber controlled means for closing said circuit, and a device in said circuit for delaying the effective energization of said magnet when its circuit is closed. 85

6. In a telephone system, a subscriber's line, a trunk line, an automatic switch for interconnecting said lines, an operating magnet for said switch, a circuit for said magnet including a high resistance relay, said magnet being inoperative when the circuit is first closed, and means controlled by said relay for increasing the flow of current 90 through said magnet to operate the same. 95

7. In a telephone system, a subscriber's line, a trunk line, an automatic switch individual to said line for extending connection to said trunk line, means controlled by the subscriber on said line for initiating the operation of said switch, and automatic means common to a plurality of said subscribers' lines for delaying the completion of the connection. 105

8. In a telephone system, a subscriber's line, a trunk line, an automatic switch individual to said line for extending connection to said trunk line, an operating magnet for said switch, a circuit for said magnet, means for closing said circuit, and means for preventing the immediate energization of said magnet after the circuit is closed. 110

9. In a telephone system, a subscribers' line, a trunk line, an automatic switch individual to said line for extending connection to said trunk line, an operating magnet for said switch, a circuit for said magnet normally open at two points, a line relay energized upon the removal of the receiver to close said circuit at one point, and automatic means effective to close said circuit at the other point after a predetermined time. 115

10. In a telephone system, a subscriber's line, a trunk line, an automatic switch in- 120

125

130

dividual to said line for extending connection to said trunk line, subscriber controlled means for initiating the operation of said switch, and automatic means common to a plurality of said subscribers' lines effective to introduce a definite time interval between the initial operation and the final connecting operation of said switch.

11. In a telephone system, a subscriber's line, a trunk line, an automatic switch for connecting said lines, subscriber controlled means for initiating the operation of said switch when making a call, and automatic means common to a plurality of said subscribers' lines for introducing a definite time interval between the initial operation and the final connecting operation of said switch every time a call is made.

12. In a telephone system, subscribers' lines, trunk lines, automatic switches for connecting calling lines with idle trunk lines, means controlled by calling subscribers for initiating the operation of said switches, and automatic means common to said switches effective to introduce a definite time interval between the initial operation and final connecting operation of any switch.

13. In a telephone system, subscribers' lines, trunk lines, automatic switches for connecting said lines, a magnet for each switch for operating the same, a circuit for said magnet, means controlled from a subscriber's line for closing said circuit, means for delaying the closure of said circuit, and automatic means for delaying the operation of said magnet after the closure of said circuit.

14. In a telephone system, subscribers' lines, an automatic switch for connecting said lines, a magnet for operating said switch, a circuit for said magnet, means controlled from a subscriber's line for closing said circuit, and automatic means for de-

laying the operation of said magnet after the closure of said circuit. 45

15. In a telephone system, subscribers' lines, trunk lines, automatic switches for connecting said lines, an operating magnet for each of said switches, a circuit for said magnet normally open at two points, a line relay energized upon the removal of the receiver to close said circuit at one point, automatic means effective to close said circuit at the other point after a predetermined time, and means for opening said circuit at another point when said magnet is operated.

16. In a telephone system, subscribers' lines, trunk lines, automatic switches for connecting said lines, an operating magnet for each switch, a circuit for said magnet normally open at two points, a line relay energized upon the removal of the receiver to close said circuit at one point, automatic means common to a plurality of said subscribers' lines effective to close said circuit at the other point after a predetermined time, and means when said magnet is operated for opening said circuit at another point to thereby prevent the operation of a second switch at the same time. 60

17. In a telephone system, a subscriber's line, a trunk line, an automatic switch for connecting said lines, an operating magnet for said switch, a circuit for said magnet 75 including a high resistance relay, said magnet being inoperative when the circuit is first closed, and means controlled by said relay for short circuiting a portion of said resistance to thereby increase the flow of 80 current through said magnet to operate the same.

Signed by me at Chicago, Cook county, State of Illinois, this 11th day of December, 1916.

TALBOT G. MARTIN.
